UNITED STATES PATENT OFFICE.

MICHAEL E. CONCANNON, OF CHICAGO, ILLINOIS.

PROPORTIONAL SPACER.

1,351,889.

Specification of Letters Patent. Patented Sept. 7, 1920.

Application filed November 15, 1919. Serial No. 338,216.

To all whom it may concern:

Be it known that I, MICHAEL E. CONCANNON, a citizen of the United States, residing at Chicago, in the county of Cook and State 5 of Illinois, have invented certain new and useful Improvements in Proportional Spacers, of which the following is a specification.

One of the objects of the invention is to 10 provide an instrument that will automatically divide the distance between two objective points into a plurality of subdivisions of uniform extent.

Another object is to provide an instrument 15 which will automatically divide the distance between two objective points into a plurality of parallel lines and subdivide each line, the divisional points being of substantially uniform extent and in staggered 20 relation.

Another object is to provide an instrument having a plurality of designating points provided with perforated pivoted connections within which to insert a prick 25 punch, or the like, to mark the points of subdivision.

Another object is to utilize a pantograph structure comprising a series of hinged together strips or blades, to provide a series 30 of parallelograms in which the pivoted joints are hollow, through which to indicate the spaced apart points.

Other, further and more specific objects 35 of the invention will become readily apparent, to persons skilled in the art, from a consideration of the following description when taken in conjunction with the drawings, wherein—

Figure 1 is a top plan view of a device 40 made in accordance with the invention.

Fig. 2 is a similar view enlarged and showing parts broken away.

Fig. 3 is a side elevation of Fig. 2.

Fig. 4 is a transverse section, taken on 45 line 4—4 of Fig. 3.

Fig. 5 is a similar view, taken on line 5—5 of Fig. 2.

In all the views the same reference characters are employed to indicate similar 50 parts.

In the drawings an embodiment of the in-

vention is shown in which two bars 10 and 11 are axially slidable with respect to each other. The bar 10 is provided in its upper surface with a dove-tail slot 12, the bar 11 having a corresponding tenon slidable in the slot. The bar 10 is provided with a series of spaced apart perforations 13, through which a bolt 14 is insertable, so as to hold the bars in adjusted position. Screwed into the 60 end of the bar 11, as at 15, is a threaded bolt having an elongated, rectangular head 16. Passing diametrically through the head 16 are a series of perforations 17, spaced apart irregular distances, and other similar 65 perforations 17' at substantial right angles to the perforations 17 in the same planes as the perforations 17, so that when the head 16 is rotated one-fourth of a revolution the bolt 14 may be placed in the transverse perforation, or in any one of the perforations 70 that are in line with the perforations 13 in the bar 10. By this means the bars may be accurately adjusted with respect to each other, as to the degree to which the outer 75 ends of the bars may be separated. Secured to each end of the bars 10 and 11 are heads 18 and 19, respectively. The heads 18 and 19 are substantial duplicates with the exception that the portion 20 of the head 19 is 80 raised somewhat above the level of the portion 21 of the head 18, so that the bar 11 may slide freely over and above the bar 10 and to provide an opening 42 through which the bar 10 may slide, so that the 85 bottom portions 22 and 23, respectively, may be of the same length. Each of the heads is provided with an elongated vertical slot 24 and a parallel plate 25 separated by spacing washers 26. A series of straps or plates 90 27 and 28 are pivoted together at their ends and at central intermediate points to form a series of parallelograms constituting a substantial pantograph structure. A hollow threaded bolt 29, having an axial opening 95 30, and a head on one end and screw threaded shank on the other end, passes through contiguous ends or parts of the blades or straps 27 and 28. The terminal ends, 32 and 33 of the pantographic structure, are secured in the heads 22 and 23, respectively, 100 by nuts 34 and other similar nuts, threaded

on the bolts 29, which secure the straps together but permit free pivotal movement thereof. The other ends 35 and 36 of the pantographic structure are vertically movable in the slots 24.

Now it is manifest that when the pantographic structure is extended the adjacent terminal pivotal points 35 and 36 will be further extended, as will also the intermediate pivotal points 37 and 38. When the heads 22 and 23 are brought closer together, the distance between the heads will be automatically divided by the pantographic structure into as many points as there are pivots between the bars or blades 27 and 28 and when the structure is moved to extended or contracted position the terminal ends 35 and 36 will move vertically in the slots 24.

The scale or index 40 and 41, on the respective bars 10 and 11, indicate the distance of separation of the heads 22 and 23 and after the heads have been separated the elongated head 16, of the bolt 15, may be rotated until one of the holes 17 is brought into register with the holes 13, to produce fractional adjustment, whereupon the bolt 14 is inserted in the registering holes and the two bars 10 and 11 are thus held in separated position.

In laying out the rivet holes on boiler sheets, the structure is very advantageous as in such instances the holes are frequently to be made in staggered relation. When the total distance of separation is given the number of divisional points in a line will equal the number of rectangular structures included between the heads.

On a boiler sheet of a given length, in which a given number of perforations or holes are to be made to receive the rivets, it is the usual custom to divide the distance by use of a pair of dividers, or otherwise, and to indicate the divisional points with a prick punch or the like. By the use of the instrument herein disclosed, the total distance to be perforated, is determined by the distance of separation of the heads 23 and 24, and after they have been separated accordingly the perforated pivots will indicate the distance of separation of adjacent holes, provided the corresponding number of rectangular structures have been placed between the heads for determining the number of holes in a given line desired. The upper line, in which the terminals 35 and 36 are located, is parallel with the intermediate line in which the pivotal points 37 are located and they are also parallel with the lower line so that the holes, or prick punch marks will appear in the boiler sheet in staggered relation. All three of the lines may be used or any one or two, as desired and of course it is manifest that any number of bars 27 and 28 of suitable length may be

included between the heads 22 and 23, depending upon the number of holes to be made in the sheets.

When the distance of separation between the heads 22 and 23 is to be relatively short the bar 11 may be removed and the bar 10 only, used, in which event it would slide through the perforation 42 made in the part 20 of the head 19, and the structure 16, shown at the right of this head, may be employed instead of the structure 16, shown intermediate the heads for the purpose of holding the heads in fixed relation. A filler block may be placed in the perforation 42 when the perforation is not in use.

The pointer 44, on the bar 10, coöperates with the scale or graduated division 47, to indicate the distance of separation between the heads.

After the heads have been separated and fixed in the holes 30 and by striking the punch on the end, in the usual manner points will be made in the sheet for producing such indications. When the instrument is raised from the plate, the points for the holes will be probably indicated a uniform distance apart and when necessary in staggered relation.

While a single embodiment of the invention has been shown for clear disclosure, it will be manifest to persons skilled in the art that many changes may be made in the general configuration, disposition of the parts within the scope of the appended claims.

Having described my invention, what I claim is:

1. An instrument of the character described having in combination two bars overlapping and slidably longitudinally of each other; a head on one end of each bar; a pantograph structure having its terminal ends connected to the respective heads, and a punch guide carried by the pivoted joints of the pantograph structure.

2. An instrument of the character described having in combination two bars overlapping and slidably longitudinally of each other; a head on one end of each bar; a pantograph structure having its terminal ends connected to the respective heads; a punch guide carried by the pivoted joints of the pantograph structure and adjustable means for separating the heads and for securing the bars together.

3. An instrument of the character described having in combination two bars overlapping and slidably longitudinally of each other; a head on one end of each bar; a pantograph structure having its terminal ends connected to the respective heads and having perforated pivots connecting its parts thereof together through which a punch may be passed and adjustable means for separating heads and for securing the bars together.

4. An instrument of the character described having in combination two bars overlapping and slidale longitudinally of each other; a head, having a slot, on one end of each bar; a pantograph structure having one of its terminal ends pivoted to each of the heads and its other end slidale in the re-
spective slots; means to secure the bars together in adjusted position and a punch guide carried by pivoted joints of the pantograph structure. 10
5. In testimony whereof I hereunto subscribe my name.

MICHAEL E. CONCANNON.
